United States Patent Office.

WILLIAM BLÜM, OF NEWARK, NEW JERSEY.

Design No. 3,604, dated August 10, 1869.

DESIGN FOR ORNAMENTING HARNESS-TRIMMINGS.

The Schedule referred to in these Letters Patent and making part of the same:

To all whom it may concern:

Be it known that I, WILLIAM BLÜM, of Newark, county of Essex, and State of New Jersey, have originated and designed a new Ornament for Harness-Trimmings; and do hereby declare that the following is a general description thereof, reference being had to the accompanying drawings, making part of this specification.

The nature of my invention consists in stamping or impressing on the leather or other covering of harness-rings and buckles, and on vulcanized-rubber or metallic harness-rings, and buckles, &c., a series of leaves or foliage, radiating from a straight line or common centre, and in such manner as to appear somewhat like a continuous rope, for the purpose of ornamenting the said rings and buckles, and giving to a set of harness on which they may be employed, a unique and beautiful appearance, as illustrated in the accompanying drawings, of which—

Figure 1 represents the bit or mouth-piece of a bridle, the ornamentation on the rings of which represents my design, and

Figure 2, a strap and buckle, the latter representing my design.

In the said drawings—

A, (fig. 1,) indicates the mouth-piece or bridle-bit; B B, the reins; C C, the connecting-rings, covered with leather or vulcanized rubber; and

D, the ornamentation on the same.

F F, (fig. 2,) indicate straps united by a buckle, F, which may be of metal or covered, and representing my design, D.

Having described my invention,

What I claim, and desire to secure by Letters Patent, is—

The design for ornamenting the rings and buckles of harness-trimmings, herein set forth.

In testimony whereof, I have hereunto set my signature.

WILLIAM BLÜM.
